MATERIAL HANDLING APPARATUS

Waldemar C. Ewaldson, Millington, N. J., assignor to Western Electric Company, Incorporated, New York, N. Y., a corporation of New York

Application October 15, 1943, Serial No. 506,455

6 Claims. (Cl. 259—1)

This invention relates to material handling apparatus, and more particularly to apparatus for handling carbon compounds for use in lapping dies.

An object of the invention is to provide a simple, efficient and practical apparatus for handling material, particularly carborundum compounds.

With this and other objects in view, the invention comprises a receptacle for a material movable relative to an electrically driven circulating means, under the control of a switch, and including a control element movable with the receptacle relative to the switch to render the switch actuatable only when the receptacle is in a given position relative to the circulating means.

Other objects and advantages will be apparent from the following detailed description when considered in conjunction with the accompanying drawings, wherein:

Fig. 1 is a side elevational view of the apparatus, portions thereof being broken away;

Fig. 2 is a top plan view of the apparatus, portions thereof being broken away;

Fig. 3 is a front elevational view of the apparatus, portions thereof being broken away;

Fig. 4 is a fragmentary side elevational view of a portion of the apparatus, this view being taken substantially along the line 4—4 of Fig. 2;

Fig. 5 is a fragmentary detailed sectional view taken substantially along the line 5—5 of Fig. 3, and

Fig. 6 is a fragmentary detailed sectional view taken along the line 6—6 of Fig. 4.

Referring now to the drawings, reference numeral 10 indicates a bracket having an inverted L-shaped portion 11 fixed to a support 12 as at 14. The entire contour of the bracket will not be described, as it is believed clearly shown in the various figures of the drawings.

On a shelf portion 15 of the bracket 10, a motor 16 is mounted, this constituting the power means for the apparatus. The motor is included in a circuit (not shown) under the control of a switch 17 which is of the push button type, it having a stop button 18 and a start button 19. The switch 17 is also mounted upon what might be termed a central portion 20 of the bracket 10 in any suitable manner (not shown). Integral with the central portion 20 of the bracket is a tubular portion 23 which houses bearings 24 for rotatably supporting a shaft 25. A sheave 26, mounted upon the upper end of the shaft 25, together with a sheave 27, mounted on the shaft 55

28 of the motor 16, aided by a belt 29 operatively connect the shaft 25 to the motor. A pump housing 30 is mounted as at 31, upon the lower end of the tubular portion 23, and has an impeller 32 disposed therein and fixedly mounted upon the shaft 25, completing what is termed a circulating unit. An outlet for the pump, which is composed of the housing 30 and the impeller 32, is indicated at 33, communicating with the compartment within the housing as indicated at 34 (Fig. 5). Other means (not shown) may be provided to return the material to the receptacle. Another impeller or agitating element 35 is mounted upon the lower end of the shaft 25 for a purpose hereinafter described.

A receptacle or bucket 38 of the contour shown has vertically extending hook-shaped arms 39 fixed at diametrically opposed positions, notches 40 in the upper ends thereof being adapted to receive trunnions 41. The trunnions 41 are carried by the outer ends of levers 42 which are mounted upon the outer ends of a shaft 43. The shaft 43 is journaled in suitable bearings in the bracket 10 and has a lever 44 fixed thereto intermediate its ends, as illustrated in Fig. 2. A nut 45 is pivotally supported by the outer end of the lever 44 through the aid of a spindle 46 integral with the nut and held against displacement relative to the lever by a fixed collar 47. An operating screw 48, threadedly disposed in the nut 45, has a hand wheel 50 mounted upon the outer end thereof and supported for rotation, but against axial movement, by a bearing element 51. The bearing element 51, through the aid of an integral spindle 52, is journaled in a bearing portion 53 of the bracket 10 and is held against axial displacement through the aid of a fixed collar 54.

By viewing Figs. 2 and 6, it will be noted that the trunnion 41 at the side adjacent the switch 17 has a projecting portion 58 receivable in an elongate aperture 59 of a control element 60. As illustrated in Figs. 1 and 4, a control element extends upwardly from its connection with the projection 58 to a position near the upper end of the portion 11 of the bracket 10, and has a portion 61 which extends substantially across the face of the switch 17 with an inwardly projecting guard portion 62. A sleeve 63, square in cross-section, is secured to the element 60 by suitable means such as welding, and is slidably mounted upon a guide bar 65. The guide bar is similar in cross-section to the sleeve 63 excepting the lower portion 66 thereof, this portion being enlarged for mounting, as at 67, upon the ad-

jaçent portion of the bracket 10. Spaced apertures 68 and 69 are disposed in the element 60, to respectively provide access to the push buttons 18 and 19 of the switch 17.

Referring momentarily to the bucket 38, handles 70 are provided therefor for use in positioning the bucket in connection with the trunnions 41 and for removing the bucket therefrom when it is desirable to replenish the bucket with the material, which in the present instance is 10 a carborundum compound indicated generally at 71.

When the apparatus is in use, the bucket or receptacle is in the upper position shown in solid lines in Figs. 1 and 3 with the stop button 15 18 of the switch accessible to the operator, for example at the end of the day when the operation of the apparatus is stopped. If the apparatus remains idle for an extended period of time, such as overnight, the carborundum dust, in the water vehicle of which the material is composed, will settle during this time interval and become substantially a solid mass in the lower portion of the receptacle. To protect the pump portion of the apparatus against damage and to assure a thorough mixing of the material prior to the circulation of the material to other apparatus, it is necessary to move the element 60 20 downwardly until the aperture 69 registers with the push button 19. At this time the receptacle 38 will also be lowered, moving the solid or settled portion of the material 71 away from the pump unit. This is brought about through rotation of the hand wheel 50, to rotate the screw 48 to move the nut 45 thereon to cause counter-clockwise movement of the shaft 43 (Fig. 1) until the aperture 69 registers with the push or start button 19. At this time the button 19 may be actuated to close the switch 17 to cause energization of the motor 16 to drive the shaft 25, causing operation of the impellers 32 and 35. At this time interval, however, the bucket or receptacle 38 is in its lowermost position. It is necessary, therefore, to reverse the operation of the screw 48 through the aid of the hand wheel 50, to move the receptacle upwardly into its uppermost position. The size of the threads of the screw 48 and the associated nut 45 will aid in determining the speed of travel of the receptacle 38 upwardly. Thus it is possible to limit the speed of movement of the receptacle upwardly, giving the impeller 35 sufficient time to thoroughly mix the material as the settled portion thereof is brought into registration with the impeller. Thus during operation of the apparatus, the switch 17, that is the stop button 18 thereof, is accessible to stop the apparatus, but through the aid of element 60, the start button 19 is accessible only when the receptacle is moved to its lowermost position.

Although specific improvements of the invention have been shown and described, it will be understood that they are but illustrative and that various modifications may be made therein without departing from the scope and spirit of this invention as defined by the appended claims.

What is claimed is:

1. A material handling apparatus comprising a receptacle for a material, a unit for circulating the material, a motor adapted to actuate the unit, a switch having starting and stopping members actuatable for starting and stopping the

motor, a start switch member actuatable to start operation of the motor, a stop switch member actuatable to stop the motor, means to cause movement of the receptacle with the material between a circulating position and a non-circulating position relative to the unit, and an element movable with the receptacle to respectively render the start and stop switch members accessible for actuation only when the receptacle is in its circulating and non-circulating positions.

2. A material handling apparatus comprising a receptacle for a material, a unit for circulating the material, a motor adapted to actuate the unit, means to lower and raise the receptacle to move the material free of the unit or surround the unit with the material, a stop switch member actuatable to stop the motor, a start switch member, and a guard movable with the receptacle to cover the start switch member and render it accessible for actuation only when the receptacle is in its lowered position.

3. A material handling apparatus comprising a receptacle for a material, a unit for circulating the material, a motor adapted to actuate the unit, means to lower and raise the receptacle to move the material free of the unit or surround the unit with the material, a stop switch member actuatable to stop the motor, a start switch member, means to render the start switch member accessible for actuation only when the receptacle is in its lowered position, and means to agitate the material during the raising of the receptacle.

4. A material handling apparatus comprising a receptacle for a material, a unit for circulating the material, a motor adapted to actuate the unit, means to lower and raise the receptacle to move the material free of the unit or surround the unit with the material, a stop switch member actuatable to stop the motor, a start switch member, and an element movable with the receptacle to render the start switch member accessible for actuation only when the receptacle is in its lowered position.

5. A material handling apparatus comprising a receptacle for a material, a unit for circulating the material, a motor adapted to actuate the unit, means to lower and raise the receptacle to move the material free of the unit or surround the unit with the material, a stop switch member actuatable to stop the motor, a start switch member, and a guard movable with the receptacle and having apertures therein to render the start and stop switch members respectively accessible when the receptacle is in its lowered and raised positions.

6. A material handling apparatus comprising a receptacle for a material, a unit for circulating the material, a motor adapted to actuate the unit, means to lower and raise the receptacle to move the material free of the unit or surround the unit with the material, a stop switch member actuatable to stop the motor, a start switch member, a guard movable with the receptacle and having apertures therein to render the start and stop switch members respectively accessible when the receptacle is in its lowered and raised positions, and an impeller driven by the unit to agitate the material during the raising of the receptacle.

WALDEMAR C. EWALDSOHN.
